(57) **CLAIM**

An ornamental design for a lift for a pickup truck, as shown and described.

DESCRIPTION

FIG. 1 is a perspective view of a lift for a pickup truck showing my new design;

FIG. 2 is a top plan view thereof;

FIG. 3 is a left elevation view thereof;

FIG. 4 is a bottom plan view thereof;

FIG. 5 is a rear elevation view thereof;

FIG. 6 is a front elevation view thereof;

FIG. 7 is a right elevation view thereof; and,

FIG. 8 is a perspective view of the lift for pickup truck of FIG. 1 in a lowered position.

In the drawings, the broken lines depict a pickup truck and form no part of the claimed design.
